UNITED STATES PATENT OFFICE.

THOMAS B. ABERCROMBIE, OF WELDON, IOWA.

MOLD FOR CONCRETE CULVERTS.

No. 921,497.

Specification of Letters Patent.

Patented May 11, 1909.

Application filed July 30, 1908. Serial No. 446,095.

To all whom it may concern:

Be it known that I, THOMAS B. ABERCROMBIE, a citizen of the United States, residing at Weldon, in the county of Decatur 5 and State of Iowa, have invented a certain new and useful Mold for Concrete Culverts, of which the following is a specification.

The object of my invention is to provide a mold of simple, durable and inexpensive 10 construction, especially adapted for use in forming concrete culverts of comparatively great length and small diameter, said mold being so arranged that after the culvert is formed the entire mold may be quickly and 15 easily removed from the culvert without the necessity of an operator getting inside of the culvert, and further to provide a mold of this kind that may be readily, quickly and easily set up for use after it has been with- 20 drawn from a culvert.

My invention consists in the construction, arrangement and combination of the various parts of the device whereby the objects contemplated are attained as hereinafter more 25 fully set forth, pointed out in my claims and illustrated in the accompanying drawings, in which—

Figure 1 shows a longitudinal sectional view through a mold embodying my invention. Fig. 2 shows a detail plan view of the abutting ends of the brace rings, the movable member of one end being shown in position for withdrawing the ring from a culvert. Fig. 3 shows a transverse sectional view of a mold embodying my invention with the edges of the mold proper in overlapping positions. Fig. 4 shows a like view with the edges of the mold proper being shown in engagement with each other. Fig. 40 5 shows an end view of the mold without the supporting rings in a partially collapsed position, and Fig. 6 shows a perspective view of one of the mold bracing rings.

Referring to the accompanying drawings, 45 the mold is composed of a number of supporting rings and a number of mold sections. Each supporting ring comprises two semi-circular members 10 and 11, one end of each member being connected by the hinge 50 12. On the other end of the member 11 is a lug 13 and on the other end of the member 10 is an extension 14 pivotally connected with the part 10 by the pin 15. This extension 14 is provided with a lug 16 of 55 greater length than the lug 13 and having an opening 17 therein to receive a rod or

wire 18. The end of the part 10 to which the extension is pivoted is preferably round at 19 as shown in Fig. 2 and the lug 16 is also preferably round as shown in Fig. 2. 60 I also provide two mold members, each of which consists of two segmental body portions 20 connected by a hinge 21. These body portions may be made of any desired material. I prefer, however, to make them of 65 sheet metal and when so made they can be used in forming culverts of different diameters. When they are used as shown in Fig. 4 with the edges of the sections in engagement with each other, then a culvert may 70 be made of the maximum diameter. If it is desired to make a culvert of less diameter, the ends of the parts 20 may be placed in overlapping positions as shown in Fig. 3 and the sheet metal may be bent to form a 75 round culvert.

In use I first place the supporting rings in position with the lugs 16 and 17 thereof in engagement with each other. Then the culvert members 20 are placed in position 80 with their abutting ends arranged at the central portions of the supporting rings as shown in Fig. 1. All of the lugs 14 are connected by means of rods 18. Then the concrete may be placed in position and after 85 it has sufficiently set and hardened the operator may, by pulling upon one end of the wire 18, first move all of the lugs 14 to position at right-angles to the ring sections 10. When this is done, the section 11 will move 90 toward the section 10 and thus the diameter of the rings will be reduced to such an extent that they may be bodily withdrawn from the interior of the mold by the wire 18. Then when this is done the sections 20 95 will no longer be supported by the rings and hence they will collapse and fall into the center of the culvert from which they may be easily withdrawn.

I claim as my invention.

100

1. An improved collapsible culvert, comprising a supporting ring formed of two sections hinged together, a pivoted extension on the free end of one section designed when in one position to engage the free end 105 of the other section, and designed when in another position to stand clear of the free end of the other section to permit the ring to collapse, and two mold sections, each comprising two segmental body portions 110 hinged together.

2. In a device of the class described, the

combination of a number of mold sections each comprising two segmental body portions hinged together, and a number of supporting rings, each comprising two segmental members hinged together, an extension pivoted to the free end of one member of each ring, said supporting rings being designed to engage the inner surfaces of the mold members at the point where the ends thereof engage each other, and means for connecting all of the said extensions for turning them at right-angles to the ring members to which they are pivoted.

3. In a device of the class described, the combination of a number of mold sections, each comprising two segmental members hinged together and a supporting ring

formed of two segmental members hinged together, a lug fixed to the free end of one of said members, and a pivoted extension 20 at the free end of the other member, said extension having a lug thereon of greater length than the aforesaid lug, and the end of the member to which the extension is pivoted being rounded, said extension being 25 provided with a shoulder to engage said rounded end, and a rod connected to the lug of said extension for the purposes stated.

Des Moines, Iowa, July 9, 1908.

THOMAS B. ABERCROMBIE.
